200,030

SEWING MACHINE

Frederick G. Creter, Bricktown, N.J., assignor to The
Singer Company, a corporation of New Jersey

Filed Apr. 8, 1963, Ser. No. 74,330

Term of patent 14 years

(Cl. D70—1)

Fig. 1.

Fig. 2.

Fig. 6.

Fig. 3.

Fig. 7.

Fig. 4.

Fig. 5.

FIG. 1 is a front perspective view of a sewing machine showing my new design,

FIG. 2 is a rear perspective view of the thread spool unwinding portion of the sewing machine shown in solid lines of FIG. 1,

FIG. 3 is a front elevational view thereof,

FIG. 4 is a rear elevational view thereof,

FIG. 5 is a top plan view thereof,

FIG. 6 is a left end elevational view thereof, and

FIG. 7 is a right end elevational view thereof.

The essential features of my design reside in the portion shown in solid lines on the drawing.

I claim:

The ornamental design for a sewing machine, as shown and described.
